UNITED STATES PATENT OFFICE.

AUGUSTIN J. CHEVRETTE AND VICTOR H. JENNINGS, OF WORCESTER, MASSACHUSETTS, ASSIGNORS TO CROMPTON & KNOWLES LOOM WORKS, OF WORCESTER, MASSACHUSETTS, A CORPORATION OF MASSACHUSETTS.

WEFT-REPLENISHING MAGAZINE FOR MULTISHUTTLE LOOMS.

Application filed July 19, 1926. Serial No. 123,277.

This invention relates to a magazine for holding reserve supplies of weft for the different shuttles in a multi-shuttle loom. In such looms, it is sometimes desirable to use 5 different types of bobbins in the same magazine and these bobbins are not always of the same length or tip diameter.

It is the general object of our invention to provide an improved construction in a weft 10 replenishing magazine, by which said magazine is adapted to hold and deliver bobbins of substantially different dimensions.

In the preferred form of the invention, we have shown a magazine capable of holding 15 either relatively long bobbins of small tip diameter or relatively short bobbins of a larger tip diameter.

Our invention further relates to arrangements and combinations of parts which will 20 be hereinafter described and more particularly set forth in the appended claims.

A preferred form of the invention is shown in the drawings in which—

Fig. 1 is a sectional side elevation of a magazine, showing the outer or tip-retaining portion thereof;

Fig. 2 is an enlarged detail sectional plan view, taken along the line 2—2 in Fig. 1;

Fig. 3 is a detail sectional elevation of one 30 of the cradles, taken along the line 3—3 in Fig. 4;

Fig. 4 is a partial side elevation of one of the cradles, looking in the direction of the arrow 4 in Fig. 3;

Fig. 5 is an enlarged view of one of the give-way devices which support the tips of 35 the bobbins during transfer; and

Fig. 6 is a plan view of said device, looking in the direction of the arrow 6 in Fig. 5.

Referring to the drawings, we have shown 40 a portion of a magazine frame 10 supported on cross rods 11 which extend to and are secured in the main or head portion of the magazine frame (not shown). The frame 10 is 45 provided with vertical ribs or flanges 12 forming guideways defining separate compartments for the different tiers of bobbins.

These flanges are of a special construction, 50 as best shown in Fig. 2, and each flange is provided with an inner shoulder 13, so that two distinct guideways are formed between each pair of flanges 12.

The inner and narrower guideway 14 is adapted to receive the tip of a long and rela-

tively small bobbin B, and the wider outer 55 guiding portion 15 is adapted to receive the tip of a shorter bobbin B' of a larger tip diameter. The bobbin B is of the type commonly used for worsted yarn, and the bobbin B' is of the type more commonly used for 60 woolen yarn.

The butt portions of the bobbins are of the usual type and of the same size, and the head end of the magazine is of the usual construction and is therefore not shown in the drawings.

With the construction described, it will be seen that each compartment of the magazine may be used interchangeably for either type 70 of bobbin B or B' and that either or both of these bobbins will be securely retained in position.

It is the usual practice to provide cradles 75 20 for supporting the lowermost bobbin in each compartment and for releasing a single bobbin upon indication of weft exhaustion. These cradles, as shown herein, are in general of the usual type but are of a special construction at the tip supporting portion, adapting them for use with both types of 80 bobbins.

Each cradle is provided with an outer flange portion 21 adapted to receive and support the relatively small tip of a bobbin B and with an inner supporting portion 22 85 adapted to receive and support the tip of a bobbin B'. Each type of bobbin is thus centered and supported in the same axial position and will be released and delivered for transfer upon indication of weft exhaustion. 90

The usual provision is made for yielding release of the tips of the bobbins during transfer, but the tip-supporting member 30 of the give-way device is of a special construction, particularly adapted to handle 95 bobbins of different lengths and diameters, such as are indicated at B and B'.

For this purpose, the member 30 is provided with the usual tip-supporting portion 31 and flange 32 by which a bobbin of the 100 type indicated at B will be supported and held from axial movement during transfer, in the usual manner. We have also provided a second or supplementary supporting portion 33 adjacent the portion 31 and separated therefrom by a shoulder 34. This portion 33 is so positioned that it will cooperate with a shorter bobbin of larger diam-

eter, such as B', guiding the same accurately during transfer.

By the provision of these three changes in a weft carrier magazine, namely, the provision of guideways 12 forming vertical compartments of different widths for the tips of two different types of bobbins, and the provision of cradles and give-way devices each having specific provision for adapting them to use with the same different types of bobbin, we have produced a magazine in which these two different types of bobbins may be used interchangeably, thus substantially increasing the range of utility of the magazine.

Having thus described our invention and the advantages thereof we do not wish to be limited to the details herein disclosed otherwise than as set forth in the claims, but what we claim is:—

1. In a loom, a magazine frame having guideways for the bobbin tips, said guideways having portions of different widths adapted to receive and center bobbins of different lengths and having tip portions of different diameters.
2. In a loom, a magazine frame having guideways for the bobbin tips thereon, said guideways having an outer guiding portion of greater width and an inner guiding portion of less width, and said guideways being adapted to receive and center bobbins of different lengths and having tip portions of different diameters.

3. In a loom, a magazine frame having a plurality of bobbin guiding members thereon extending across and at both sides of the two extreme end portions of the bobbin and effective to closely engage and definitely position bobbins of different lengths and having tip portions of different diameters, and cradles co-operating with said guiding members, each having a portion effective to closely engage the tip of a bobbin of one length and one tip diameter to advance said bobbin to transfer portion, and having another portion at a less distance from the axis of said cradle effective to closely engage the tip of a second bobbin of substantially less length and of substantially greater tip diameter to advance said bobbin to transfer position.

4. In a loom, a magazine frame having a plurality of bobbin guiding members thereon effective to laterally and definitely position bobbins of different lengths and having tip portions of different diameters, and give-way devices for guiding said bobbin to transfer position, said devices having guiding portions at different elevations and separated by an abrupt shoulder, one of said portions being positioned to closely engage a long and small tipped bobbin and the other portion being positioned to closely engage a relatively short and large tipped bobbin.

In testimony whereof we have hereunto affixed our signatures.

AUGUSTIN J. CHEVRETTÉ.
VICTOR H. JENNINGS.
